J. G. WILSON.
Tailor's Measure.

Patented May 3, 1833.

May 3 1833

James G. Wilson (City of New York.)

The Schedule referred to in these Letters Patent, and making part of the same, containing a description in the words of the said James G. Wilson himself of his improvement in the Rule, for cutting garments.

To all to whom these presents shall come, I James G. Wilson of the City of New York send greeting, —

Be it known that I the said James G. Wilson have invented a new and useful Rule for cutting garments, not known or used before in the cutting of garments, which is described as follows to wit:

The rule is made two inches wide, more or less and twelve inches long more or less, and is made of any material suited for a graduated instrument, the broad measure of a man's breast and gives the distances of the divisions on the ruler, first the size is taken and any given number for a man's breast may be found on that ruler commencing from twenty four inches and opposite to six inches on the quota and running to eleven and one half inches, these numbers are one fourth of the size around a man commencing at the end of the quota where the inches commence their number on the opposite side of the ruler, and against the fourth inch commences a scale of thirds and running to the end, being a sixth of the distance around a man, on the opposite side from these numbers, and commencing at three eighths of an inch, is a quota or space left in the ruler up to five and three quarter inches in which is a scale of smaller divisions of the breast, being fourths, eightths, sixteenths, and thirty two seconds also three, six and twelve eighths, these scales are held to the plane by a groove being left at each end of the opening of the ruler so as to admit the end of the scales, this groove is covered top and bottom by metal, to admit the ends of these scales of sufficient strength to hold them on their plane, they may also be held in by sprung covers placed on the ruler, four sizes may be placed on one rule, one of them occupying each ruler.

756ex

I do not claim the combination of the members in the construction of a piano stool, nor the materials of which it is made, but I do claim
the particular mode of the construction and improvements, and the
use to which these improvements may be applied.

New York December 29th 1882.
